US0D1002591S

(12) **United States Design Patent** (10) **Patent No.:** **US D1,002,591 S**
(45) **Date of Patent:** **** Oct. 24, 2023**

(54) **EARPIECE**

(71) Applicant: **Apple Inc.**, Cupertino, CA (US)

(72) Inventors: **Robert Brunner**, Glen Ellen, CA (US);
Christopher Kuh, San Francisco, CA (US)

(73) Assignee: **Apple Inc.**, Cupertino, CA (US)

(**) Term: **15 Years**

(21) Appl. No.: **29/888,926**

(22) Filed: **Apr. 6, 2023**

Related U.S. Application Data

(60) Continuation of application No. 29/825,906, filed on Feb. 7, 2022, now Pat. No. Des. 983,772, which is a continuation of application No. 29/803,833, filed on Aug. 16, 2021, now Pat. No. Des. 942,972, which is a continuation of application No. 29/750,393, filed on Sep. 14, 2020, now Pat. No. Des. 928,125, which is a continuation of application No. 29/685,126, filed on Mar. 26, 2019, now Pat. No. Des. 896,204, which is a continuation of application No. 29/609,404, filed on Jun. 30, 2017, now Pat. No. Des. 844,588, which is a continuation of application No. 29/540,941, filed on Sep. 29, 2015, now Pat. No. Des. 792,378, which is a continuation of application No. 29/501,037, filed on Aug. 29, 2014, now Pat. No. Des. 740,260, and a continuation of application No. 29/496,755, filed on Jul. 16, 2014, now Pat. No. Des. 741,299, which is a continuation of application No. 29/441,334, filed on Jan. 3, 2013, now Pat. No. Des. 712,382, said application No. 29/501,037 is a division of application No. 29/441,334, filed on Jan. 3, 2013, now Pat. No. Des. 712,382.

(57) **CLAIM**

The ornamental design for an earpiece, as shown and described.

DESCRIPTION

FIG. 1 is a top rear perspective view of an earpiece showing the claimed design;

FIG. 2 is a front view thereof;

FIG. 3 is a rear view thereof;

FIG. 4 is a side perspective view thereof;

FIG. 5 is a top view thereof; and,

FIG. 6 is a bottom view thereof.

The broken lines in the figures show portions of the earpiece or environment that form no part of the claimed design.
